John J. Thompson's
Stomach Doctor

The schedule referred to in these Stomach Doctor and making part of the same containing a description in the name of the said John J. Thompson of himself of his improvement in the Trapp called the Curious Elasticated Food Trapp.

The great deficiency hitherto experienced for the want of a good Trapp in Stomach affections when it is taken into consideration the large proportion of mankind that are afflicted with this painful malady, has rendered an investigation of constructing a more efficacious Trapp particularly interesting and necessary for effecting a radical cure or mitigating the distress of those afflicted from the frequent fatality resulting from improper treatments.

Before describing my improvement I shall briefly state a few of the many imperfections existing in the different types hitherto presented to the publick. In the conveyance there are undoubtedly many just objections grounded on the true principle of surgery.

1st) They afford no support to the muscular fibres around the operation but on the contrary more frequently prove injurious by destroying the natural tone particularly in exaggrate cases when a great degree of support must necessarily be afforded admitting little if any elasticity or lateral motion.

2nd) Those on the principle of being concurvare are equally objectionable in consequence of the liability of the Trapp not affording the lateral motion becoming easily impeded under its weight for the necessary influence or pressure together with the concurvity of the part not pressing immediately on the opening of the bowel can not form the viscus making the slight adhesion on the one side by adhering on the other by support

right property can be effected by agglutination."

3 and lastly. The great evil attending every lump was particularly the pain, ulcerating and offensive smell which naturally, must arise a the materials used becoming so readily absorb the perspirable matter of the body rendering it hard and inconvenient particularly during the warmer seasons of the year,

By this improvement all the foregoing evils are obviated agreeably to the following specification, perking satisfied of all the advantages happily combined in the discovery.

This improvement of the circular spring, consists of a thin piece of steel about one inch broad and the length required for the size of the person, with two holes at the extreme end for fastening the appendages to adjust the lump on the body. On the other end there are 4 small holes $\frac{3}{4}$ of an inch apart in a straight line for lengthening or shortening the spring as circumstances may require, when applied on the pad. After the spring is properly shaped the whole is covered with jaquard silk or linseed as a protection against the perspirable matter of the human body which however naturally has the tendency of destroying the elasticity & rendering it perfectly useless in a short time.

The pad. This is constructed of an oval or round two and a half inches long by two & one eighth inches broad, prepared of tin for any other metal, convex on the outside (without any indentation (concavity,) on the centre half an inch in depth gone with $\frac{3}{4}$ three eighths in diameter, forming on the inner side the centre convex & the surrounding plate concave on which is placed a pad of gum elastic. By this discovery if only a few of the adhesive qualities of the plate be retained it would be considered a valuable acquisition in the formation of the pad, among which we might enumerate durability, plasticity & ulcerating. The last though not the least, will alone be of great importance which is considerable in all these respects though giving a greater consideration on the greater power

plate to the shape. The forming this from the gun metal is first prepared and shaped in imitation of the oral plate or comes without the cap, on the lower side convexly with the depression in the centre on the upper side (that one applying on the body) the concavity formed in the centre of the concavity in the centre of the lower side is considerably flattened so as to present a more even surface on the centre of the orifice through which the viscus protrudes in its usual occasions. The edge remaining elevated leaving a concavity or depression around the concavity in the centre in which moreover the lower side is accurately fitted to the plate already described with some adhesive ingredient. On the external surface of the oral plate there is a ring secured in the centre of the concavity already described, three eighths of an inch high with a cover on the upper edge and within a spiral spring confined by means of a screw cap two eighths of an inch with a round hole in the centre through which passes a trap door five eighths of an inch in length with a small round plate riveted at the end resting on the spiral spring, at the other end there is a slide in order to pass through one end of the circular spring with a small screw passing thro' the centre of the slide, perforations in the circular spring to make it stationary leaving an intermediate space on said end of three eighths of an inch to act on the spiral spring. By this great rotary or lateral motion afforded by the spiral spring the pad remains permanent by being placed perfectly free from any injurious effects or action of the circular spring to which it is subject by the numerous positions the body is placed during the operations of the day. In describing the improvement for fastening the trap around the body, I shall principally advert to the advantages of the trap which were from three to six inches long fastened in the centre end of the circular spring and the other on a strip of leather about two inches in breadth of requisite length to pass around on the part where it is fastened by means of a stationary buckle. The spiral wires are now covered with a piece of thin

7/20/1831 (d2Bx)

or muslin double the length of the wire so as not to impair the elasticity, being of great importance for easy comfort yielding readily to the different positions of the body.

The whole of circular spring including the wire appurages are now covered with buck skin or silk previously lined and fastened at the other end of the circular spring. The pad is now covered completely with a silk or velvet case drawn with a ribbon and tied on the back of the pad. Having now finished the whole trap you place the end of the circular spring already described through slide on the back of the pad and fasten the same by passing the small screw thru the centre of the slide & hole in the circular spring. By this mode it can be lengthened or shortened as the user may require. By this new improved Patent Elastic Pad by Salami agreeably to specification the formation of the improved Patent Elastic Pad for said purpose. Together with the spiral spring and all other springs confined with a screw cap on the back of the oval or round plate prepared from any of the different metals with a small trap rod passing through the centre with a slide on the top and a small plate at the other end resting on any spring fastening the japanned or lined circular spring theron by which the rotary & lateral motion is derived from said trap rod acting on the spiral spring. Also a right of the elastic appurages for fastening all traps on the body by means of spiral wires all of which I find to answer perfectly well.
